UNITED STATES PATENT OFFICE.

FRANK P. GLAZIER, OF CHELSEA, MICHIGAN.

VAPOR-BURNER.

SPECIFICATION forming part of Letters Patent No. 617,568, dated January 10, 1899.

Application filed August 31, 1896. Serial No. 604,410. (No model.)

To all whom it may concern:

Be it known that I, FRANK P. GLAZIER, a citizen of the United States, residing at Chelsea, in the county of Washtenaw and State of Michigan, have invented certain new and useful Improvements in Vapor-Burners, of which the following is a specification, reference being had therein to the accompanying drawings.

10 My invention relates to oil-burners of the Bunsen-burner type, in which air is commingled with the vapor formed above the wick, causing it to burn with a blue flame.

The invention consists in the peculiar construction, arrangement, and combination of parts, as more fully hereinafter described and claimed.

15 In the drawings, Figure 1 is a perspective view of my burner, partly broken away and showing the parts in position for lighting. Fig. 2 is a vertical central section through the burner as in use.

20 A and B are respectively the inner and the outer casing of the wick-tube. C is the wick contained therein, which is provided with a suitable raising and lowering device, (indicated at D.)

25 E is a central air-passage formed within the tube A, and F is an annular passage between the wick-tube and a surrounding casing G.

30 H is a flaring ring secured to the upper end of the casing G.

I is an annular perforated casing surrounding the wick-tube and resting on the ring H, the top a of which forms a shelf and is preferably on a line with the top of the wick-tube.

35 J is a perforated tube forming an upward extension of the tube A and preferably supported on a bead or ledge b.

40 K is a cap at the upper end of the tube J, having the imperforate sides c and the top d provided with a circular row of apertures e. This cap is also preferably provided with the central aperture f and the downwardly-projecting tube g, which serves to divide up the air-current in such a way as to give a proper amount of air for combustion at all points and at the same time prevent any sudden strong air currents or blasts from affecting the flame

45 and causing the stove to smoke.

50 L is a perforated tube resting on the upper end of the tube B, which latter is provided

with the outwardly and upwardly extending supporting-flange h.

M is an imperforate casing surrounding the 55 tube L and secured thereto by the apertured rings or spiders N N'. The casing M normally rests upon the top of the casing I, preferably around an offset i thereon. At several points on its lower edge it is provided with the down- 60 wardly-projecting cams j, which pass through apertures k in the casing I and are adapted to raise the casing M when the latter is rotated.

O is a perforated diaphragm extending 65 across the tube A.

The burner thus constructed is preferably mounted by supporting the ring H on a shelf P, secured to a suitable stand (not shown) provided with an oil-tank connected with the 70 wick-tube.

To light the burner, the operator rotates the casing M, which is raised by the cams j, lifting with it the perforated tube L. This will disclose the wick, which may be lighted, 75 after which the casing M and tube L are lowered again by turning them in the reverse direction. As soon as the tube L is lowered the flame will rise to the top of the tube, while at the same time air will be drawn in through 80 the perforations in it and the tube J, which commingle with the vapor of the oil and cause the latter to burn with a blue or Bunsen-burner flame.

It will be noticed that in lighting the burner 85 only the outer wall of the perforated extension of the wick-tube is moved, the inner one or tube J remaining stationary. The advantage of this is that there is much less danger of putting out the flame than if both tubes 90 were moved.

The imperforate portion of the cap K at the upper end of the tube J, which projects slightly above the upper end of the tube L, has the effect of making a steadier flame than 95 if the perforations extended to the top of the tube and the latter was the same height as the outer tube.

The whole arrangement of the air-passage and screens is designed to produce a uniform 100 flame and one free from smoke.

What I claim as my invention is—

The combination with the annular wick-tube and a perforated upward extension thereof

having a movable outer wall, of a perforated outwardly-extending annular shelf at the upper end of said wick-tube, an imperforate annular casing surrounding and secured to the outer wall of said perforate extension and resting on said shelf, and means for raising said imperforate casing and perforate wall by the rotation thereof, comprising the cams *j*

normally projecting through apertures in the shelf. 10

In testimony whereof I affix my signature in presence of two witnesses.

FRANK P. GLAZIER.
